Attorneys.

UNITED STATES PATENT OFFICE.

FREDERICK E. SCHMITT, OF GREEN BAY, WISCONSIN, ASSIGNOR TO THE MILWAUKEE SANDER MANUFACTURING COMPANY, OF SAME PLACE.

ROLLER-FRAME ADJUSTMENT FOR SANDERS.

SPECIFICATION forming part of Letters Patent No. 596,232, dated December 28, 1897.

Application filed July 6, 1897. Serial No. 643,550. (No model.)

To all whom it may concern:

Be it known that I, FREDERICK E. SCHMITT, of Green Bay, in the county of Brown and State of Wisconsin, have invented certain new and useful Improvements in Roller-Frame Adjustments for Sanders; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The main object of my invention is to prevent the roller-frame from rocking or tipping and causing the polishing drums or cylinders to gouge into the work and thus produce uneven imperfect surfaces, particularly as the stuff enters and leaves the machine.

It consists, essentially, of a device for taking up play between the roller-frame and the screws by which it is adjustably supported, as hereinafter particularly described, and pointed out in the claims.

In the accompanying drawings like letters designate the same parts in both figures.

Figure 1 is a vertical longitudinal section of a portion of a sanding-machine to which my improvement is applied, the plane of the section being indicated by the line 1 1, Fig. 2; and Fig. 2 is a horizontal section in the plane indicated by the line 2 2, Fig. 1.

A designates a portion of the main frame, B the bed, C one of the polishing drums or cylinders, D D lower feed-rollers, E the upper roller-frame, F F upper feed-rollers, and G an upper presser-roller opposite the polishing-cylinder, all of the usual or any suitable construction and arrangement in or for this class of machines.

The roller-frame E is supported at the corners by vertical screws H, which are threaded therein and have bearings at their upper and lower ends in corner-posts I, mounted on the main frame or bed of the machine. The several adjusting-screws carrying the roller-frame are connected in the usual way by shafts J and intermeshing bevel-gears h and j, as partially shown in Fig. 1, so as to simul-

taneously raise and lower said frame equally 50 at its four corners.

It is well known that in machines of this kind the polishing-cylinders must be constructed and adjusted with great accuracy, and the bearings of the cylinders and feed-rollers must also be accurately adjusted and firmly supported without play in order to produce satisfactory work. In machines having the upper feed-rollers carried by a frame which is adjustably supported by vertical 55 screws threaded therein, as shown in the drawings, the backlash or play of the screws in the roller-frame allows it to tip more or less forward or backward. This movement of the frame, occurring particularly when the material enters and leaves the machine, causes the polishing-cylinders to gouge into the work and thus produce wavy and imperfect surfaces. To cure this defect is the purpose of 60 my improvement, which consists of a device 65 for preventing the backlash or for taking up 70 the play of the adjusting-screws in the roller-frame.

Upon each of the screws H, below the roller-frame or that part of the frame with which it 75 engages, is a nut or threaded sleeve K, as shown in Fig. 1. Each of these sleeves is formed at its upper end with a cup-shaped spring-seat k and at its lower end with a notched rim or flange k'. A heavy spiral 80 spring L is interposed between the frame and each nut or sleeve, as shown in Fig. 1. These springs are made of sufficient strength to sustain the weight of the roller-frame and the mechanism which it carries. 85

There are dogs or detents for holding the sleeves K, when properly adjusted, from turning upon the screws H. They may be attached to the roller-frame, as shown in the drawings, so as to be readily disengaged from and engaged 90 with any of the notches in the flanges k' of the sleeves K. As shown in the drawings, they are longitudinally slotted and secured by bolts m in recesses formed in the under side of the roller-frame. By loosening the 95 bolts m the detents may be withdrawn from engagement with the notched flanges k' for the purpose of adjusting the sleeves K to vary

the tension of the springs L, as desired. When these adjustments have been made, the detents M are thrust forward into the adjacent notches in flanges k' and secured in place by 5 the screws m.

In practice the sleeves K are turned upwardly on the screws H until the springs take up all play between the upper sides of the threads in the frame and the under sides of 10 the threads on the screws and firmly support said frame in that position. By this means the frame is prevented from tilting up at either end and down at the opposite end when a piece of material enters or leaves the machine, and even perfect surfaces are insured 15 if the machine is in other respects properly constructed and adjusted.

I claim—

1. In a sanding-machine the combination 20 with the roller-frame and vertical adjusting-

screws engaging the same, of sleeves threaded on said screws and springs interposed between said sleeves and frame, substantially as and for the purposes set forth.

2. In a sanding-machine the combination 25 with the roller-frame and vertical adjusting-screws engaging threaded holes in said frame and supported in bearings in the main frame, of sleeves threaded on said screws, dogs or catches for holding said sleeves from turning 30 on said screws and spiral springs interposed between said sleeves and frame, substantially as and for the purposes set forth.

In testimony that I claim the foregoing as my own I affix my signature in presence of 35 two witnesses.

FREDERICK E. SCHMITT.
